EDGE-GUIDED POINT MARKER FOR
INSOLES

Bernhardt Jorgensen, Marblehead, Mass., assignor to United Shoe Machinery Corporation, Flemington, N. J., a corporation of New Jersey

Original application March 26, 1945, Serial No. 584,763. Divided and this application December 28, 1945, Serial No. 637,621

34 Claims. (Cl. 33—189)

1

This invention relates primarily to punching mechanisms, although in some aspects it is not thus limited in its applicability, the present application being a division of a copending application for Letters Patent for improvements in Shoe machines, Serial No. 584,763, filed on March 26, 1945, on which Letters Patent No. 2,420,665 were granted on May 20, 1947. The invention is herein illustrated as embodied in mechanism attached to a toe-lasting machine constructed generally as disclosed in United States Letters Patent No. 2,324,509, granted on July 30, 1943, on an application of mine, but modified in some respects as shown in later disclosures of mine including Letters Patent No. 2,391,461, granted on December 25, 1945.

It has been proposed, as disclosed in the last-mentioned Letters Patent, to position shoes in the above-mentioned toe-lasting machine in proper relation to the lasting means by a member engaging the insole of each shoe in an indentation previously formed in the insole in predetermined relation to the edge of the shoe bottom. An object of the present invention is to provide improved mechanism for forming or punching such an indentation, or hole, in the insole, and such punching mechanism is herein shown as attached to the frame of a toe-lasting machine of the above-mentioned character and operated by power derived from that machine. Such power is supplied by fluid under pressure, the machine having means for developing and for maintaining such pressure during a cycle of operations, as fully disclosed in the above-mentioned Letters Patent No. 2,324,509.

The insole-punching attachment herein shown includes a punch which is operated to form the required indentation or hole in the insole while the shoe is supported by the hands of the operator, and further includes gage mechanism which is movable laterally of the shoe to position the latter relatively to the punch prior to the operation of the punch. The position of the shoe lengthwise is further determined by a member which serves in response to the presentation of the shoe by the operator to render both the punch and the gage mechanism operative. More particularly, movement of this member closes the electrical circuit of a solenoid which operates a valve to admit fluid obtained from the fluid-pres-

sure system of the lasting machine to fluid-pressure means for operating the gage mechanism, from which fluid-pressure means a restricted passage for the fluid leads to other fluid-pressure means provided for actuating the punch, thus insuring the proper sequence in the operation of the gage mechanism and that of the punch. To cause the parts to return to their starting positions after the punching operation the electrical circuit is broken by the movement of the punch-operating mechanism. For imparting the operative movement to the punch the construction shown comprises a spring-operated hammer which is retracted against the resistance of a spring and is then released to the action of the spring by the fluid-pressure means associated therewith. The hammer is movable in a path substantially at right angles to the path of movement of the punch and acts on the punch through an intermediate member which is mounted for swinging movement, the hammer and its spring being parts of a self-contained hammer unit pivotally connected to this swinging member. Various novel features of the invention are to be recognized in the organization thus provided.

The above-mentioned gage mechanism, in the construction herein shown, comprises two pairs of opposite side gages, one pair being displaced lengthwise of the shoe from the other pair and the gages of each pair being connected together for movements toward or from each other independently of the movements of the other pair. To insure that the shoe will be properly positioned, the different pairs of gages are operated respectively by different fluid-operated members which are movable independently of each other by the pressure of fluid thereon. Conveniently, as shown, these members are pistons movable in opposed relation to each other in a chamber common to both of them. It will be evident that with respect to this feature, as well as some others, the invention is not limited in utility to insole-punching mechanisms.

The above and other features of the invention, including various novel details of construction and combinations of parts, will now be more particularly described with reference to the accompanying drawings and thereafter pointed out in the claims.

In the drawings:

Fig. 1 is a view in front elevation of the greater portion of a toe-lasting machine such as disclosed in the above-mentioned Letters Patent, having attached thereto insole-punching mechanism in which novel features of the invention are embodied;

Fig. 2 is a plan view on an enlarged scale of the upper portion of the insole-punching mechanism with the parts in their starting positions;

Fig. 3 shows the same portion of the insole-punching mechanism in elevation as viewed from the right with reference to Fig. 2;

Fig. 4 is a section on the line IV—IV of Fig. 2;

Fig. 5 shows in elevation a portion of the insole-punching mechanism as viewed from the left with reference to Fig. 2, with the parts in operative relation to a shoe shown in section;

Fig. 6 is a section on the line VI—VI of Fig. 2;

Fig. 7 is a vertical sectional view of an accumulator provided for storing fluid obtained from the fluid-pressure system of the lasting machine to operate the insole-punching mechanism, and of parts associated with the accumulator;

Fig. 8 is a section on the line VIII—VIII of Fig. 7; and

Fig. 9 is a section substantially on the line IX—IX of Fig. 6, with parts broken away.

The toe-lasting machine shown in Fig. 1, as fully disclosed in the previously mentioned Letters Patent, is provided with a plurality of fluid-operated instrumentalities which operate on the shoe in the course of a cycle of power operations of the machine. As disclosed particularly in Letters Patent No. 2,391,461, the shoe is presented to the machine by the operator with the bottom of the forepart of the insole in engagement with a plate 2 provided with a spur 4 which enters a small hole or indentation previously formed in the forepart of the insole to position the shoe lengthwise and laterally in proper relation to the lasting instrumentalities, and it is clamped against the plate 2 substantially at the beginning of the cycle of operations by upward movement of a fluid-operated toe rest 6. Operating fluid, preferably oil, is supplied by a continuously driven pump (not shown) from a reservoir or sump 8 to a pressure chamber or manifold (also not shown) in which the fluid is maintained under pressure by the pump during each cycle of operations.

To provide the insole with the small hole or indentation to receive the spur 4 there is supported on an arm 10 fast on the right-hand side of the frame of the machine the greater portion of the insole-punching mechanism embodying features of the present invention. This mechanism includes a casting 12 on the front end portion of which are rotatably mounted two rolls 14 (Figs. 1, 2 and 9) arranged to engage the bottom face of the forepart of the insole in locations spaced apart widthwise of the shoe when the shoe is presented thereto bottom upward by the operator. A third roll 16 is rotatably mounted on a plate 18 (Figs. 6 and 9) secured to the lower face of the casting 12 and is arranged to engage the insole in a location nearer the toe end thereof than the rolls 14 and substantially midway between the sides of the toe. The three rolls thus serve as a shoe rest and facilitate movement of the shoe in a toeward direction after the operator has presented the shoe against them. Such movement of the shoe is limited by engagement of its toe-end face with an arm 20 which serves as an end gage for the shoe and

serves also another purpose hereinafter described. Further to position the shoe laterally and angularly in proper relation to a punch hereinafter described for punching the hole in the insole, there are provided two pairs of side gages 22 and 24 including respectively arms 26 and 28 arranged to extend lengthwise of the shoe and pivotally mounted on studs 30 on the casting 12. The two gages 22 are arranged to act on the shoe at the opposite sides of the forepart in the vicinity of its ball portion, and the two gages 24 are arranged to act thereon at the opposite sides of its toe portion. Each arm 26 carries a stud 32 on which is pivotally mounted a small block 34 faced with leather or other appropriate material 36 for contact with the shoe, the block being movable about the stud 32 short distances limited by its contact with the arm 26 to permit it to adjust itself to the shoe. Each arm 28 has fast thereon a block 38 (Fig. 4) faced with leather 40 or other suitable material and provided with an upwardly extending stem 42 secured to the arm by a nut 44. Integral with the arms 26 are arms 46 (Fig. 9) extending inwardly toward each other and connected together by gear teeth so that the arms 26 will swing equal distances in unison toward or from the shoe. Similarly the arms 28 have integral therewith inwardly extending arms 48 connected together by gear teeth so that the arms 28 also will swing equal distances in unison toward or from the shoe. Mounted in one of the arms 46 is a plunger 50 (Fig. 6) pressed by a spring 52 against one face of the casting 12, the spring tending to swing the two arms 26 outwardly away from each other. Similarly a spring 54 controlling a plunger 56 (Fig. 9) mounted in one of the arms 48 tends to swing the two arms 28 in outward directions. Also integral with one of the arms 26 is a third arm 58 provided with a roll 60 in engagement with the outer end of a piston 62 movably mounted in one end of a cylinder 64 formed in the casting 12. Another similar piston 62 movably mounted in the other end of the cylinder 64 is engaged on its outer end by a roll 66 supported by an arm 68 which is integral with one of the arms 28. Each piston 62 is provided on its outer end with a flange 70 arranged to engage the casting 12 to limit inward movement of the piston in the cylinder 64. It will therefore be evident that the flanges 70 limit the outward swinging movements of the gage arms 26 and 28 under the influence of the springs 52 and 54. For adjusting the arms 26 toward or from each other the arm 58 is provided with an eccentric stud 72 on which the roll 60 is mounted, and similarly the roll 66 is mounted on an eccentric stud 74 (Fig. 4) on the arm 68 for adjusting the arms 28 toward or from each other.

From the above description it will be evident that the two gages 22 are operated by one of the pistons 62 and the two gages 24 by the other piston, each pair of gages being thus movable independently of the other pair by fluid admitted to the cylinder 64 in the common chamber between the pistons so that all the gages are moved as required properly to centralize the shoe between them. As disclosed in Letters Patent No. 2,324,509, operating fluid is maintained under pressure in the fluid-pressure system of the lasting machine only during each cycle of operation of the machine, and in order that the insole-punching mechanism may be operated if desired when the lasting machine is idle there is provided an accumulator 76 (Fig. 7), more particularly

hereinafter described, which is charged with fluid by the lasting machine and stores the fluid under pressure for operating the insole-punching mechanism. The fluid is conducted from the accumulator to the cylinder 64 through a pipe 78. Admission of fluid from the accumulator to this pipe is controlled by a valve 80 (Fig. 7) mounted in a chamber 82 at one end of a casting 84 which is part of the accumulator and is supported on the side frame of the lasting machine. The valve 80 is a sleeve valve slidably mounted on a tube 86 which is divided by a partition 88, one end of the tube communicating with the accumulator and the other end with the pipe 78. When the valve is in its initial position, as shown in Fig. 7, the accumulator is not in communication with the cylinder 64 and the latter is open to exhaust through the pipe 78 and ports 90 in the tube 86, these ports communicating with the chamber 82 from the upper portion of which the fluid is returned to the sump 8 (Fig. 1) through a pipe 92. Movement of the valve 80 toward the left with reference to Fig. 7 opens communication through an annular chamber 94 in the valve between the ports 90 and other ports 96 in the tube 86, thus admitting fluid from the accumulator to the pipe 78. Such movement of the valve is effected through a lever 98 (Figs. 7 and 8) pivotally mounted on a stud 100 which is supported by a lug 102 extending downwardly into the chamber 82 from a cover plate 104 over the chamber, this lug also supporting a splash shield 106 positioned over the ports 90 and 96. At its lower end the lever is provided with a pin 108 extending into a groove 110 in the valve. The valve is held normally in its initial position by a spring 112 in engagement at one end with a washer 114 which bears on a lug 116 extending upwardly from the cover plate 104 and in engagement at its other end with a block 118 pivotally mounted on the upper arm of the lever 98 which extends through a slot in the cover plate. A rod 120 is pivotally mounted on the lug 116 and extends through the spring and the block 118. The upper end of the lever 98 is connected by a link 122 to the armature 124 of a solenoid 126 supported on the top of the casting 84. Accordingly, when the electrical circuit of the solenoid is closed the lever 98 is operated to move the valve 80 into position to admit fluid from the accumulator to the pipe 78. Such closing of the electrical circuit is effected by the pressure of the toe-end face of the shoe against the previously mentioned arm 20 (Fig. 6) when the shoe is presented by the operator to the insole-punching mechanism. This arm is pivotally mounted on a pin 128 on the casting 12 and is controlled by a spring 130 which is positioned between a lug 132 on the hub portion of the arm and a portion of the casting 12 and tends to swing the arm in a clockwise direction with reference to Fig. 6. Movement of the arm in this direction is limited by its engagement with an edge face 134 of the casting 12. In this manner the normal position of the arm is determined. Pivotally mounted at 136 on the lower end of the arm is a block 138 which is further controlled as hereinafter described and has adjustably secured to its lower face a plate 140. One edge of this plate is arranged to engage a knob 142 fastened to a switch member 144 which extends into a switch box 146 on the casting 12 and by inward movement against the resistance of a spring (not shown) is arranged to close the electrical circuit of the solenoid. The switch, not shown in detail,

is one of a well-known type requiring only a very short movement of the switch member 144 to close the circuit. Movement of the arm 20 by the shoe is limited by a screw 148 which is threaded in the lug 132 and is arranged to engage the casting 12. Accordingly the arm is effective not only as a switch-closing member but also as an end gage for the shoe to determine the distance from the end of the toe of the hole punched in the insole. To form the hole or indentation in the insole there is provided a punch 150 (Figs. 5 and 6) comprising a pin vertically movable in a bore in the casting 12 and having a conically pointed lower end for engagement with the insole. On the upper end of the pin is formed a plunger 152 movable downwardly in another bore in the casting against the resistance of a return spring 154. The plunger 152 is engaged on its upper end by a hardened contact piece 156 carried by a member 158 which is pivotally mounted on a pin 160 on the casting 12. The member 158 is provided with two downwardly extending fingers 162 between which is a pin 164 fast on the casting 12 for limiting movements of the member in opposite directions by engagement with the fingers. As the parts are shown in Fig. 6, the member 158 is held by the spring 154 in the position determined by engagement of the pin with one of the fingers, the punch 150 being retracted above the insole of any shoe presented to the machine. When the punch is operated to punch the hole in the insole its movement is limited by engagement of the pin 164 with the other finger 162 of the member 158, its movement being sufficient to punch the hole only part way through the insole, as illustrated in Fig. 5. The movement of the member 158 to operate the punch 150 is effected by mechanism which will now be described. Pivotally connected by a pin 166 to this member is a block 168 to which is rigidly connected a rearwardly extending rod 170, the block and the rod being parts of a self-contained hammer unit 172. The rod 170 extends through a cylinder 174 which also is a part of the hammer unit and is provided with a roll 176 resting on a flat face 178 formed on a portion of the casting 12. This face accordingly supports the hammer unit against the force of gravity. Surrounding the rod 170 inside of the cylinder 174 is a spring 180. Mounted on the rod is a washer 182 which is seated against inwardly extending flanges 184 (Fig. 2) of the cylinder 174 and itself provides a seat for one end of the spring. The other end of the spring is engaged by a washer 186 also mounted in the cylinder 174 and confined on the rod 170 by a nut 188. A narrow rearwardly extending portion 190 (Fig. 2) of the block 168 lies in a vertical slot in the front end of the cylinder 174 between the flanges 184 to permit relative movements of the block and the cylinder in directions lengthwise of the cylinder while preventing the cylinder from turning relatively to the block. It will be evident that the spring 180 by its pressure on the washer 182 tends to move the cylinder 174 forwardly toward the block 168, and by the spring the cylinder is thus held normally in a relation to the block determined by engagement of portions of the block with the front end face of the cylinder, as illustrated in Fig. 2. Pivotally mounted on a pin 192 (Fig. 6) on the casting 12 is a lever 194 on the upper end of which is secured a hardened wear plate 196 arranged to engage the edge of a similar plate 198 secured to the cylinder 174. Also mounted on

the upper end of the lever 194 is a roll 200 engaged by one end of a piston 202 movably mounted in a cylinder 204 formed in the casting 12. The piston carries a screw 206 which by engagement with the inner end wall of the cylinder limits the inward movement of the piston in the cylinder. Mounted in the lower end portion of the lever 194 is a plunger 208 which engages one face of the casting 12 and is controlled by a spring 210. This spring, therefore, tends to swing the lever 194 in a counterclockwise direction with reference to Fig. 6 and to move the piston 202 to the limit of its inward movement determined by the screw 206.

Operating fluid is admitted to the inner end of the cylinder 204 from the previously mentioned cylinder 64 through a passage 212. By the action of the fluid the piston 202 is forced outwardly and swings the lever 194 in a clockwise direction as far as permitted by engagement of the lower end of the lever with that face of the casting 12 which is engaged by the plunger 208. In the course of this movement of the lever the plate 196 by engagement with the plate 198 imparts to the cylinder 174 lengthwise movement in a direction away from the block 168 and thereby compresses the spring 180 through the action of the washer 182 on the spring, this movement of the cylinder being not of sufficient extent to cause the rearwardly extending portion 190 of the block 168 to be withdrawn from the slot in the cylinder. Prior to the completion of the movement of the lever 194 the plate 196 slips downwardly past the edge of the plate 198, thus releasing the cylinder 174, whereupon the spring 180 impels the cylinder suddenly in the reverse direction until its front end strikes against the block 168. By its momentum the cylinder thus acts as a hammer to swing the member 158 and thereby to impart operative downward movement to the punch 150 against the resistance of the spring 154, the movement of the member 158 being limited by the pin 164 as hereinbefore described. The passage 212 connecting the cylinder 64 to the cylinder 204 is a restricted passage such as to retard the flow of the fluid to the cylinder 204 and thereby to insure that the gages 22 and 24 will properly position the shoe before the punch is operated. In the return of the parts to starting positions the hammer unit is lifted by the engagement of the plate 196 with the plate 198 to permit the return of the lever 194.

Pivottally connected at its lower end to the previously mentioned block 138 (Fig. 6) is a rod 214 which extends upwardly through an opening in a rearwardly extending arm 216 of the member 158, and confined on this rod by nuts 218 is a washer 220 having a curved lower face engaging a complementally curved face on the arm. It will be evident that, when the member 158 is moved as above described to operate the punch, the arm 216 is swung in an upward direction, and through the connection between this arm and the block 138 the block also is swung upwardly and carries the plate 140 away from the knob 142 on the switch member 144. In response to such release of the switch member the electrical circuit of the solenoid 126 is broken, whereupon the valve 80 is returned to its initial position by the spring 112, thereby releasing the fluid from the cylinder 64 and from the cylinder 204 connected thereto. This permits the gages 22 and 24 to be swung away from the shoe by the springs which control them and permits the piston 202 and the lever 194 to be returned by the spring 210. It will be

understood that when the shoe is removed the arm 20 is returned by the spring 130, thus permitting the plate 140 again to be moved downwardly into operative relation to the knob 142 by the block 138. To insure such return of the plate and the block there is mounted in the arm 20 a spring-pressed plunger 222 in engagement with the top face of the block.

The accumulator from which the fluid is obtained for operating the insole-punching mechanism includes a piston 224 (Fig. 7) movably mounted in a cylindrical chamber 226 in the casting 84. This piston is controlled by a spring 228 which abuts at its outer end against a plate 230 held in fixed relation to the casting 84 by screws 232. The outer end of the spring is centralized relatively to the plate 230 by a circular plate 234 which is positioned within the spring and is provided with a projection 236 extending into an opening in the plate 230. It will be understood that the piston 224 is movable outwardly in the chamber 226 against the resistance of the spring by the pressure of the fluid admitted to the chamber. The fluid for thus charging the accumulator is conducted to the chamber 226 from the fluid-pressure system of the lasting machine through a pipe 238 in which is a check valve 240 to prevent return of the fluid, as more fully disclosed in the copending application of which this application is a division. Preferably the capacity of the accumulator is such that the insole-punching mechanism may be operated three or four times without any recharging of the accumulator, although ordinarily it need be operated only once when the lasting machine is idle to prepare the first shoe for presentation to the machine. Thereafter the insole-punching mechanism will ordinarily be used to prepare a shoe while the lasting machine is operating on a shoe previously prepared and accordingly at a time when the accumulator will be charged by the lasting machine. To prevent the piston 224 from blocking the opening from the pipe 238 into the chamber 226 there is secured to the piston a plate 242 having an annular extension 244 of smaller diameter than the piston for engaging the end wall of the chamber 226 to limit the inward movement of the piston, this plate serving also to hold in place packing 246 for preventing leakage of the fluid. Any of the fluid that may escape past the piston is received in an annular groove 248 in the casting 84 and is conducted from this groove back to the sump 8 of the lasting machine through a pipe 250.

The manner of operation of the insole-punching mechanism will now be briefly summarized. Before presenting the first shoe to the lasting machine the operator presents it to this mechanism, the accumulator 76 being already charged with fluid under pressure and the fluid also filling the pipe 78 and the spaces in the cylinders 64 and 204 not occupied by the pistons 62 and 202. The operator thus presents the shoe to the punching mechanism with the bottom of the forepart of the insole in engagement with the rolls 14 and 16 and pushes the shoe lengthwise against the end gage member 20. The pressure of the end face of the shoe on this member operates the switch member 144 to close the electrical circuit of the solenoid 126, whereupon the solenoid operates the valve 80 to admit fluid from the accumulator to the pipe 78 leading to the cylinder 64. The pressure of the fluid in this cylinder then moves the pistons 62 in outward directions and thereby swings the pairs of side gages 24 and

26 inwardly to position the shoe between them relatively to the punch 150, as illustrated in Fig. 9. At the same time fluid passes from the cylinder 64 to the cylinder 204 through the restricted passage 212 for imparting outward movement to the piston 202. The movement of this piston swings the lever 194 to retract the cylinder 174 against the resistance of the spring 180 through engagement of the plate 196 with the plate 198, the cylinder being released to the action of the spring when the plate 196 is moved far enough to disengage it from the plate 198. The spring then operates the cylinder 174 as a hammer which by impact on the block 168 swings the member 158 to impart operative movement to the punch 150, the movement of the punch being limited by engagement of the pin 164 with one of the fingers 162. The punch thus forms a hole or indentation in the bottom of the insole without passing entirely through it, as illustrated in Fig. 5. As the punch is thus operated the arm 216 of the member 158 acts through the rod 214 to swing the block 138 upwardly and thus to release the switch member 144, thereby breaking the electrical circuit of the solenoid. The valve 80 is then returned by the spring 112 to its initial position, closing the outlet from the accumulator and opening the ports 90 to the chamber 82 to permit exhaust of fluid from the cylinders 64 and 204. The side gages are then returned by the springs 52 and 54, thereby moving the pistons 62 inwardly in the cylinder 64 as far as permitted by their flanges 70, and the piston 202 is returned by the spring 210 through the lever 194, the hammer unit 172 being swung upwardly by this lever to permit the plate 196 to pass the plate 198. Immediately after its operation the punch is returned by the spring 154 which also imparts return movement, limited by the pin 164, to the member 158 and to the hammer unit 172. The return of the member 158 permits the plate 140 to resume its initial relation to the switch member 144 upon return of the gage member 20 by the spring 130 when the operator removes the shoe. The operator then presents the shoe to the lasting machine in position for the spur 4 of that machine to enter the indentation formed in the insole and starts the operation of that machine. In the course of the operation of the lasting machine the accumulator is again fully charged with fluid passing through the pipe 238 to the chamber 226. The operator will ordinarily present each shoe, after the first one, to the insole-punching mechanism while the lasting machine is operating on a shoe previously operated on by that mechanism, but the charge of fluid maintained in the accumulator permits the use of the insole-punching mechanism at any time.

While the insole-punching mechanism is herein shown as operating on a shoe which has already been partially lasted, as is appropriate in view of its attachment to a toe-lasting machine to prepare shoes for immediate presentation to that machine, it will be understood that such mechanism might be used for punching holes in insoles mounted on lasts prior to the mounting of uppers on the lasts.

Having described the invention, what I claim as new and desire to secure by Letters Patent of the United States is:

1. In insole-punching mechanism, a tool constructed and arranged to form an indentation in the bottom face of an insole mounted on a last presented to the tool by the operator, gage mechanism movable to position the last and in-

sole relatively to said tool, and power-operated means for thus moving said gage mechanism and for thereafter operating the tool while the last is supported against the thrust of the tool by the hands of the operator.

2. In insole-punching mechanism, a tool constructed and arranged to form an indentation in the bottom face of an insole mounted on a last presented to the tool by the operator, gage mechanism movable to position the last and insole relatively to said tool, and automatic means for operating first said gage mechanism and then the tool in response to the presentation of the last to the tool while the last is supported against heightwise movement by the hands of the operator.

3. In insole-punching mechanism, a punch for punching a hole in an insole mounted on a last supported by the hands of the operator, means for positioning the last and insole relatively to said punch while the last is thus supported, a spring for operating the punch to punch the hole in the insole, and means for subjecting said spring to stress and for then releasing it to render it thus effective on the punch.

4. In insole-punching mechanism, a punch for punching a hole in an insole mounted on a last supported by the hands of the operator, means for positioning the last and insole relatively to said punch while the last is thus supported, a hammer for operating the punch, a spring for operating said hammer, and means for retracting the hammer against the resistance of said spring and for then releasing it to render it effective on the punch.

5. In insole-punching mechanism, a punch for punching a hole in an insole mounted on a last, means for positioning the last and insole relatively to said punch, a member mounted for swinging movement to operate the punch, and a hammer for operating said member by impact.

6. In insole-punching mechanism, a punch for punching a hole in an insole mounted on a last, means for positioning the last and insole relatively to said punch, a member mounted for swinging movement to operate the punch, a block connected to said member, a spring-operated hammer associated with said block, and means for retracting said hammer and for then releasing it to cause it by impact on the block to operate said member.

7. In insole-punching mechanism, a punch for punching a hole in an insole mounted on a last, gage mechanism movable to position the last and insole relatively to said punch, a spring-operated hammer for operating the punch, and automatic means for first operating said gage mechanism and for thereafter rendering said hammer effective to operate the punch.

8. In insole-punching mechanism, a punch for punching a hole in an insole mounted on a last, gage mechanism movable to position the last and insole relatively to said punch, a hammer for operating the punch, a spring for operating said hammer, automatic means for retracting the hammer against the resistance of said spring and for then releasing it to render it effective on the punch, and additional automatic means for operating said gage mechanism before the hammer is thus released.

9. In insole-punching mechanism, a punch for punching a hole in an insole mounted on a last, gage mechanism movable to position the last and insole relatively to said punch, fluid-pressure means for operating said gage mechanism, ad-

ditional fluid-pressure means for rendering said punch effective to punch the hole in the insole, and a single valve for admitting operating fluid to both said fluid-pressure means.

10. In insole-punching mechanism, a punch for punching a hole in an insole mounted on a last, gage mechanism movable to position the last and insole relatively to said punch, fluid-pressure means for operating said gage mechanism, a valve for admitting operating fluid to said fluid-pressure means, additional fluid-pressure means for rendering the punch effective to punch the hole in the insole, and means providing a restricted passage for the flow of fluid from said first-named fluid-pressure means to said additional fluid-pressure means to delay the operation of the punch on the insole until after the operation of said gage mechanism.

11. In insole-punching mechanism, a punch for punching a hole in an insole mounted on a last, gage mechanism, movable to position the last and insole relatively to said punch, fluid-pressure means for operating said gage mechanism, a valve for admitting operating fluid to said fluid-pressure means, a hammer for operating the punch, a spring for operating said hammer, additional fluid-pressure means for retracting the hammer against the resistance of said spring and for then releasing it to render it effective on the punch, and means providing a restricted passage for the flow of fluid from said first-named fluid-pressure means to said additional fluid-pressure means to delay the operation of the punch until after the operation of said gage mechanism.

12. In fluid-operated mechanism, a tool for operating on a workpiece, gage mechanism, movable to position the workpiece relatively to said tool, fluid-pressure means for operating said gage mechanism, means for admitting operating fluid to said fluid-pressure means, additional fluid-pressure means for rendering said tool effective on the workpiece, and means providing a restricted passage for the flow of fluid from said first-named fluid-pressure means to said additional fluid-pressure means to delay the operation of said tool on the workpiece until after the operation of said gage mechanism.

13. In insole-punching mechanism, a punch for punching a hole in an insole mounted on a last, a pair of gages connected together for movements toward each other to position the last between them relatively to said punch, another pair of gages connected together for movements toward each other further to position the last between them in a different location lengthwise of the last than said first-named gages, a fluid-operated member movable by pressure of fluid thereon to operate said first-named pair of gages, and another fluid-operated member movable by pressure of fluid thereon independently of said first-named member to operate said other pair of gages.

14. In insole-punching mechanism, a punch for punching a hole in an insole mounted on a last, a pair of gages connected together for movements toward each other to position the last between them relatively to said punch, another pair of gages connected together for movements toward each other further to position the last between them in a different location lengthwise of the last than said first-named gages, two fluid-operated members movable by pressure of fluid thereon to operate said different pairs of gages respectively, and means providing a chamber

common to both said members and in which they are movable by the fluid.

15. In fluid-operated mechanism, the combination with means for operating on a workpiece, of a pair of gages connected together for movements toward each other to position a portion of the workpiece between them, another pair of gages connected together for movements toward each other to position another portion of the workpiece between them, a fluid-operated member movable by pressure of fluid thereon to operate said first-named pair of gages, and another fluid-operated member, movable by pressure of fluid thereon independently of said first-named member to operate said other pair of gages.

16. In fluid-operated mechanism, the combination with means for operating on a workpiece, of a pair of gages connected together for movements toward each other to position a portion of the workpiece between them, another pair of gages connected together for movements toward each other to position another portion of the workpiece between them, two pistons movable by pressure of fluid thereon to operate said different pairs of gages respectively, and a cylinder in which said pistons are thus movable in opposed relation to each other, said cylinder providing a chamber common to both pistons to receive fluid for operating them.

30 17. In insole-punching mechanism, a punch for punching a hole in an insole mounted on a last presented to the punch by the operator, a reciprocator member movable thus to operate said punch, electrical means arranged to be energized by the presentation of the last to render said member operative, and means for de-energizing said electrical means by the movement of said member.

18. In insole-punching mechanism, a punch for 40 punching a hole in an insole mounted on a last presented to the punch by the operator, mechanism movable thus to operate said punch, fluid-pressure means for rendering said mechanism effective on the punch, a valve movable to admit 45 operating fluid to said fluid-pressure means, electrical means arranged to be energized by the presentation of the last thus to move said valve, and means for de-energizing said electrical means by the movement of said punch-operating mechanism.

19. In insole-punching mechanism, a punch for punching a hole in an insole mounted on a last presented to the punch by the operator, a hammer for thus operating said punch, electrical means arranged to be energized by the presentation of the last to render the hammer thus effective on the punch, and means for de-energizing said electrical means by the action of said hammer.

60 20. In insole-punching mechanism, a punch for punching a hole in an insole mounted on a last presented to the punch by the operator, a hammer for thus operating said punch, a spring for operating said hammer, fluid-pressure means 65 for retracting the hammer against the resistance of said spring and for then releasing it to the action of the spring, a valve movable to admit operating fluid to said fluid-pressure means, electrical means arranged to be energized by the presentation of the last thus to move said valve, and means for de-energizing said electrical means by the action of said hammer.

21. In insole-punching mechanism, a punch for punching a hole in an insole mounted on a last presented to the punch by the operator, a

member mounted for swinging movement thus to operate the punch, a hammer for operating said member, fluid-pressure means for rendering the hammer effective on said member, a valve movable to admit operating fluid to said fluid-pressure means, electrical means for thus moving said valve, a switch for energizing said electrical means by the presentation of the last, and means for de-energizing said electrical means by control of said switch through the movement of said swinging member.

22. In insole-punching mechanism, a punch for punching a hole in an insole mounted on a last presented to the punch by the operator, mechanism movable thus to operate said punch, gage mechanism movable to position the last and insole relatively to said punch, electrical means arranged to be energized by the presentation of the last to cause said gage mechanism thus to position the last and insole, and means for de-energizing said electrical means by the movement of said punch-operating mechanism.

23. In insole-punching mechanism, a punch for punching a hole in an insole mounted on a last presented to the punch by the operator, mechanism movable thus to operate said punch, gage mechanism movable to position the last and insole relatively to said punch, fluid-pressure means for thus moving said gage mechanism, a valve movable to admit operating fluid to said fluid-pressure means, electrical means arranged to be energized by the presentation of the last thus to move said valve, and means for de-energizing said electrical means by the movement of said punch-operating mechanism.

24. In insole-punching mechanism, a punch for punching a hole in an insole mounted on a last presented to the punch by the operator, mechanism movable thus to operate said punch, fluid-pressure means for rendering said mechanism effective on the punch, gage mechanism movable to position the last and insole relatively to the punch, additional fluid-pressure means for thus moving said gage mechanism, electrical means arranged to be energized by the presentation of the last to admit operating fluid to both said fluid-pressure means, and means for de-energizing said electrical means by the movement of said punch-operating mechanism.

25. In punching mechanism, a punch for punching a hole in a workpiece presented to the punch by the operator, a reciprocatory member movable thus to operate the punch, electrical means arranged to be energized by the presentation of the workpiece to render said member operative, and means for de-energizing said electrical means by the movement of said member.

26. In punching mechanism, a punch for punching a hole in a workpiece presented to the punch by the operator, mechanism movable thus to operate the punch, fluid-pressure means for rendering said mechanism effective on the punch, a valve movable to admit operating fluid to said fluid-pressure means, electrical means arranged to be energized by the presentation of the workpiece thus to move said valve, and means for de-energizing said electrical means by the movement of said punch-operating mechanism.

27. In punching mechanism, a punch mounted for operative movement in a predetermined path, a hammer mounted for movement in a path at an angle to the path of movement of the punch to operate the punch by impact, and a member

mounted for swinging movement to transmit force from the hammer to the punch.

28. In punching mechanism, a punch mounted for operative movement in a predetermined path, a member mounted for swinging movement to operate the punch, a spring-operated hammer movable in a path at an angle to the path of movement of the punch to operate said member by impact, and means for retracting said hammer and for then releasing it to render it effective on said member.

29. In punching mechanism, a punch mounted for operative movement in a predetermined path, a member mounted for swinging movement to operate the punch, a rod connected to said member and extending at an angle to the path of movement of the punch, a hammer movable along said rod to operate said member by impact, a spring extending about the rod for thus moving said hammer, means on the rod providing a seat for one end of the spring, and means for retracting the hammer against the resistance of said spring and for then releasing it to the action of the spring.

30. In punching mechanism, a punch mounted for operative movement in a predetermined path, a member mounted for swinging movement to operate the punch, a self-contained hammer unit pivotally connected to said member, said unit including a hammer and a spring for impelling it to operate said member by impact, and means for retracting the hammer against the resistance of said spring and for then releasing it to the action of the spring.

31. In punching mechanism, a punch mounted for operative movement in a substantially vertical path, a member mounted for swinging movement to operate the punch, a self-contained hammer unit pivotally connected at one end to said member and extending substantially horizontally therefrom, means supporting said unit against the force of gravity, said unit including a hammer and a spring for impelling it to operate said member by impact, and means for retracting the hammer along said supporting means against the resistance of said spring and then releasing it to the action of the spring.

32. In punching mechanism, a punch mounted for operative movement in a predetermined path, a member mounted for swinging movement to operate the punch, a hammer movable in a path at an angle to the path of movement of the punch to operate said member by impact, a spring for thus moving said hammer, and a member mounted for swinging movement to retract the hammer against the resistance of said spring and by further movement in the same direction to release the hammer to the action of the spring.

33. In punching mechanism, a punch mounted for operative movement in a predetermined path, a member mounted for swinging movement to operate the punch, a hammer movable in a path at an angle to the path of movement of the punch to operate said member by impact, a spring for thus moving said hammer, an arm mounted for swinging movement to retract the hammer against the resistance of said spring and by further movement in the same direction to release the hammer to the action of the spring, and a fluid-operated member for operating said arm.

34. In punching mechanism, a punch mounted for operative movement in a predetermined path, a member mounted for swinging movement to operate the punch, a hammer movable in a path

at an angle to the path of movement of the punch to operate said member by impact, a spring for thus moving said hammer, an arm mounted for swinging movement to retract the hammer against the resistance of said spring and by further movement in the same direction to release the hammer to the action of the spring, a fluid-operated piston for thus moving said arm, and a spring for returning said arm and for thereby returning said piston.
